SOUNDPROOF WALL CONSTRUCTION

William D. Barge, Pelham, N. Y., assignor to The
George S. Holmes Co., Inc., New York, N. Y.,
a corporation of New York

Application October 11, 1932, Serial No. 637,215

7 Claims. (Cl. 72—17)

This invention relates to soundproof building construction and more particularly to the insulation and support of interior or finishing walls. One of the objects thereof is to provide a construction which will be light and resilient. Another object is to provide a simple and practical construction which can be cheaply and quickly installed without the use of skilled labor. Another object is to provide a double wall construction in which the weight of the finishing wall is more efficiently distributed over the area of the supporting wall structure. Further objects provide simple and practical means for supporting a lath and plaster wall in spaced relation to the supporting wall structure and preventing the transmission of vibration from one wall to the other.

Other objects will be in part obvious and in part pointed out hereinafter.

The invention accordingly consists in the features of construction, combinations of elements and arrangements of parts as will be exemplified in the structure to be hereinafter described and the scope of the application of which will be indicated in the following claims.

Referring to the drawing, in which similar reference characters refer to similar parts throughout the figures,

Fig. 1 is a surface view of the finishing wall embodying my invention, with portions broken away to show the construction;

Fig. 2 is a perspective view of furring strip secured by means of an insulating fastener to a supporting member; and

Fig. 3 is a view similar to Fig. 2 but showing the supporting member secured to a base or supporting wall, and the furring strip fastener occupying a position at an end of the member.

Referring now to the drawing for a detailed description of the invention, 10 indicates an inner supporting structure or base wall, which may be the outer wall of a building or a partition wall, and which may be built of concrete, terra cotta hollow tile, or other suitable material.

A suitable form of lathing 11 is supported in spaced relation to wall 10 by means of sound-insulating members 12 and 13, and furring strips 14. The lathing I employ is preferably of the fibre-back expanded metal variety which is attached to the vertical furring strips 14 in any suitable manner, as by means of tie wires or staples 15, which pass around the furring strips with their ends twisted together after piercing the fibre-back and passing through openings in the metal lathing.

The lathing serves to support a plaster finishing wall 16 in the usual manner. Instead of lath or plaster any suitable wall board may be secured to the furring strips, and it is to be understood that where the term "lathing" is employed in the claims it is intended to cover such wall board constructions.

As indicated above, my insulating supports comprise coating metal members 12 and 13 which I will now describe in detail. Each member 12, hereinafter referred to as a support, is formed of a long metal strip or sheet bent longitudinally upon itself to provide a base portion 17 and a substantially parallel flange portion 18, the relative disposition of which will be understood by reference to Figs. 2 and 3. These portions are suitably spaced, the flange portion 18 being of less depth than the base portion 17. The latter is provided adjacent its lengthwise edge with a row of holes 19, suitably spaced, through which nails or other fastening means may be driven or forced into the base wall 10. Supports 12 are secured directly to the base wall in spaced parallel relation to one another, each support extending horizontally across the wall space to be plastered. In practice I set my supports on 24-inch centers with the long edges of the flanges facing upwardly. In this position the long edge of each flange 18 becomes a supporting edge over which insulator members 13 are hung.

Members 13 resemble members 12 in form but instead of being made of long strips or sheets to produce support members, they consist of short sheets bent to provide hook-shaped members of relatively little width as compared with the length of the supports 12. Each member 13, hereinafter referred to as a fastener, has a flange 21 of substantially the same length as flange 18 and a slightly deeper flange 22 which, when a fastener 13 is seated in installed position upon a support 12, as shown in Figs. 2 and 3, extends substantially to the bottom of support 12. Each fastener is further provided with a pair of oppositely extending lugs 23 which project from the lateral edges of flange 22, as clearly appears in the drawing.

As installed in a wall structure each support 12 will support a plurality of the fasteners 13 distributed along its length at predetermined intervals. In practice I find a spacing of 16 inches from center to center satisfactory. The flanges of a fastener so supported are disposed in inter-laminar relation to the flanges of the support.

In assembling the parts of the insulator device, a strip 24 of wool felt, asbestos felt, or other

sound-deadening material is twice doubled upon itself so as to fill the space between support portion 17 and fastener flange 21, the space between the latter and support flange 18, and the space between flange 18 and fastener flange 22. The deadening strip 24 will then have the shape of the letter S and will therefore underlie the edge of flange 21 and overlie the edge of flange 18. Thus all parts of the metallic members of the insulator will be separated by sound-deadening material, as will be apparent by inspection of Figs. 2 and 3.

Having proceeded so far in the construction of a plaster covered wall, the addition of furring strips and metal lathing may be quickly and easily accomplished. Ordinarily when mounting insulators for supporting furring strips in spaced relation to a base wall, it is necessary to secure the insulators to the base wall in strict alignment in the direction of the lengths of the furring strips, in order that the latter may be fastened to the insulators. And as the said insulators are generally immovably mounted on the base wall, the alignment of the insulators requires mechanical skill and considerable care. Thus much time is lost merely in securing the insulators to the base walls in their predetermined positions.

This disadvantage is entirely absent in the installation of my device. Obviously it is a simple matter to secure the supports to the base wall in substantially horizontal position. Then the desired number of fasteners may be hooked over a support and adjusted along the support to approximately their proper positions. The construction man may then use a furring strip as a straight edge to perfect the positioning of the fasteners. Preferably the furring strips will stand vertically, wherefore a fastener on each support to which the furring strip is to be secured will be vertically aligned with each other fastener which is to support the strip.

In securing my furring strips to the fasteners I lay a tie-wire 25 across the strip, pass the ends of the wire behind the lugs 23 of the fastener, then bring them together in front of the strip and twist them together to the desired tightness. While any form of furring strip may be used, I preferably employ a channeled strip having its web placed flat against the fastener and its flanges in position to be engaged by the metal lathing. This arrangement is shown in Figs. 1 and 2.

From the foregoing description it will be obvious that not only is the plaster supporting construction light and inexpensive, but the ease with which it may be built up will be readily understood. Also, it is to be noted that any movement of the plaster wall relatively to the base wall due to expansion or contraction will not harm the structure. Slight outward movement of the plaster wall will be accommodated by the resiliency of the overlapping flanges of the insulator members, while movement in the plane of the metal lathing will merely cause a slight horizontal or vertical shifting of the insulator members with respect to one another.

In some kinds of construction it may be found desirable to reverse the mounting of the insulator members, in which case the fasteners would be secured to the base wall and the supporting members would support the plaster finishing wall. With such a construction the furring strips could be omitted and the metal lathing be attached directly to the insulator members. Such a construction might lose some of the advan-

tageous facility of erection as compared with my preferred embodiment but would result in economy of material and somewhat reduce the thickness of the completed wall structure.

It will be seen that there is provided a construction of an essentially practical nature in which the several objects of this invention are attained.

As many possible embodiments may be made of the above invention without departing from the scope thereof, it is to be understood that all matter herein set forth or shown in the accompanying drawing is to be interpreted as illustrative and not in a limiting sense.

I claim:

1. In sound-deadening building construction, in combination, a wall structure, a plurality of supports fastened horizontally to said wall structure in spaced relation to one another, a plurality of furring strip fasteners supported by each of said supports and adjustable longitudinally thereof to bring a fastener on one of said supports into vertical alignment with a fastener on another of said supports, means for attaching furring strips to said vertically aligned fasteners, and sound-deadening material interposed between coating parts of said supports and said fasteners.

2. In building construction, means for insulating lathing from a structural wall including, in combination, a structural support comprising a base portion adapted to be secured at a plurality of horizontally spaced points to the wall, and a flange portion spaced from said base portion and having an upwardly directed edge; a plurality of horizontally spaced hook-shaped members overlying the said edge of said support and comprising downwardly depending portions disposed in interlaminar relation to said base and flange portions of said support; and means for attaching said fasteners to the lathing.

3. In sound-deadening building construction, in combination, a wall structure, a plurality of long resilient supporting members secured to said wall structure in parallel spaced relation to one another, a plurality of resilient furring strip fasteners mounted in spaced relation upon each of said members by hooking thereover, a plurality of furring strips supported by said members in spaced relation thereto by attachment to said fasteners, and means for impeding the passage of sound vibrations from said furring strips to said long members.

4. In a wall construction, in combination, an inner base wall, a plurality of spaced horizontal U-shaped metal sound insulating supporting members secured to the base wall by one side so that the edges face upwardly, a plurality of individual hooking members slidably hooked over the free edges of said U-supporting members, said hooking members being approximately arranged in spaced vertical lines, each hooking member having wire engaging projections extending therefrom; spaced vertical furring strips secured by wire to their respective arranged hooking members, the said hooking members being readily moved into exact alignment with their respective furring strips; and fibre sound deadening material twice doubled upon itself to fill the space between each hooking member and its respective supporting U-member.

5. In a wall construction, in combination, an inner supporting wall, a plurality of spaced horizontal supporting members having a free edge

- and secured to the base wall so that the free edge of each faces upwardly, a plurality of individual hooking members adjustably hooked over the free edge of said supporting members, and fibre
- 5 sound-deadening material separating each hooking member from its respective supporting member, each hooking member having wire engaging portions extending therefrom and spaced furring strips vertically arranged and secured by wire to their respective hooking members being readily moved into exact alignment.
6. In a wall construction, supporting means for securing lathing to the inner wall, said means comprising spaced horizontal supporting strips secured to said inner wall and having free upwardly extending edges, hooking members slidably hooking over said free edges and separated therefrom by sound-deadening material, and spaced furring strips vertically arranged and
- 15 20 adjustably secured to said hooking members whereby said furring strips may be adjusted horizontally and vertically, and means for securing said lathing to said furring strips.
7. In a wall construction, supporting means for securing lathing to an inner base wall, comprising a plurality of long spaced horizontal supporting members which may be secured to the wall at any convenient spacing, hooking members slidably secured to said supporting members and separated therefrom by fibre sound-deadening material, and adapted for horizontal adjustment along said supports, furring strips adapted to be secured to said hooking members independently of the vertical spacing between said hooking members, said hooking members being movable into exact alignment with their respective furring strips and means for securing said lathing to said furring strips.

WILLIAM D. BARGE. 20
